[57] CLAIM

The ornamental design for an automatic animal feeder, as shown and described.

DESCRIPTION

FIG. 1 is a top, front and left side perspective view of an automatic animal feeder showing my new design;

FIG. 2 is a top, front and left side perspective view of FIG. 1 in an operating condition;

FIG. 3 is a top plan view thereof;

FIG. 4 is a front elevational view thereof;

FIG. 5 is a rear elevational view thereof;

FIG. 6 is a bottom plan view thereof; and,

FIG. 7 is a left side elevational view thereof, the right side being a mirror image thereof.

FIG. 1

FIG. 2

FIG.3

FIG.4

FIG.5

FIG.6
